UNITED STATES PATENT OFFICE

2,108,734

OIL BURNER

Josiah Howard Van Sciver, Elkins Park, Pa., assignor to Bethlehem Foundry & Machine Company, Bethlehem, Pa., a corporation of Pennsylvania

Application January 8, 1937, Serial No. 119,685

9 Claims. (Cl. 230—117)

This invention relates to improvements in oil burners, and relates more particularly to burners of the type disclosed in my prior United States Patent No. 1,973,187.

5 A principal object of the present invention is to provide a compact and simplified assembly wherein the operating parts of the burner, inclusive of the blower, the motor and the oil pump, are mounted in a manner to reduce to a minimum 10 the usual operating noises, to prevent amplification of these noises, and to preclude noises arising from vibrations set up by the operating members and transmitted to the metallic casing of the burner and through the casing to the furnace.

15 The invention will be more readily understood by reference to the attached drawings, in which:

Figure 1 is a side elevational view of a burner made in accordance with my invention;

20 Fig. 2 is a section on the line 2—2, Fig. 1;

Fig. 3 is a fragmentary section on the line 3—3, Fig. 2;

25 Fig. 4 is a view in perspective of one of the elements of the assembly, a portion of this element being broken away to show the cross sectional form of the element, and

Figs. 5, 6 and 7 are fragmentary views in perspective illustrating a detail of the construction.

With reference to the drawings, the burner 30 comprises a casing 1 providing a blower chamber 2 and discharge conduit 3 extending therefrom. The casing 1 is mounted in the present instance upon a pedestal 4 which rises from a suitable base 5. As shown in Figs. 1 and 3, the casing consists of two separable sections, 6 and 7 respectively, which are united by means of bolts 8.

At opposite sides of the chamber 2, the casing is formed with circular openings 9 and 10, and the edges of these openings form seats for a pair of rubber or other suitable resilient rings 11, one of these rings being shown in perspective in Fig. 4. Each ring is L-shaped in cross section, and in assembly the outstanding flanges 12 extend along the outer faces of the casing, as shown in Fig. 2. Each of the rings has on its inner periphery a series of inwardly projecting bosses 13, shown in Fig. 4, and one of these bosses 13a is extended for a purpose hereinafter set forth. Opposite this extended boss 13a, on the outer periphery of each ring, is a boss 14, which as shown in Fig. 3 fits into a recess 15 in the annular seat of the casing, and thereby in effect immobilizes the ring 11 with the casing.

Seating in the interior of the rings 11 and 55 against the inwardly projecting bosses 13 of the

latter is an annular structure 16, this structure consisting of the two spaced and aligned annular portions 17 and 18 which seat directly on the rings 11 and which are connected together at diametrically opposite sides by axially extending bridge portions 19 and 21. Each of the annular portions 17 and 18 comprises an outwardly extending flange, 22 and 23, respectively, which bear against the outer faces of the flanges 12 of the rings 11, as clearly shown in Fig. 2, and the member 16 is so relatively proportioned with respect to the housing 1 that the resilient rings 11 are closely confined under slight compression between these two parts. Each of the annular portions 17 and 18 of the member 16 is provided with a recess 24, which in assembly receives the extended boss 13a of the respective resilient rings 11, the member 16 thereby being immobilized with respect to the ring, and through the ring with respect to the housing 1. It will be apparent that the member 16 is thus securely mounted in the housing 1 and solely through the medium of the resilient rings 11, and that metal-to-metal contact between these parts is thereby obviated.

Secured to the annular portion 17 of the member 16 through the medium of screws 25 is an electric motor 26, and this motor in effect closes the opening at one side of the chamber 2. The shaft 27 of this motor extends axially through the chamber 2 and has secured thereto, through the medium of a hub element 28, a blower 29, this blower occupying a centrally located position within the chamber. As shown in Fig. 2, the annular portion 18 of the member 16 is extended in the axial direction at 31 and is provided at its outer end with an inwardly extending flange 32 in which is mounted a fuel pump 33. The shaft 34 of this pump is aligned with the motor shaft 27, and is connected to the latter through the medium of a suitable flexible coupling 35. The cylindrical wall 31 is provided as shown in Fig. 2 with a series of ports 36 distributed around its periphery which afford access for air to the interior of the housing 1 and to the blower 29, and this wall carries externally an apertured sleeve 37 which may be adjusted circumferentially to regulate the effective areas of the intake ports 36. A screw 38 is provided for securing the sleeve 37 to the flange 23 of the member 16 in adjusted position. Suitably secured within the annular portion 18 of the member 16 is an annular deflector 39 which directs the incoming air to the intake opening 40 in the side of the blower 29. It will be noted that by reason of the location 55

of the pump 33 within the cylindrical extension 31, the air drawn through the ports 36 by the action of the blower 29 is caused to flow over and around the pump casing, thereby exerting a cooling effect upon the pump. To the outer end of the cylindrical extension 31 is attached a casing 41 which houses the outer portions of the pump.

It will be noted from the foregoing description that through the medium of the member 16 which constitutes a common mount for the motor and the pump, and indirectly for the blower 29 which is carried by the motor shaft 27, these working parts of the burner form a unit assembly which finds through the resilient rings 11 a floating mount upon the casing 1, and that there is in this way a complete segregation of the operating parts of the burner from the casing and from the furnace structure with which the casing is assembled. By this means, the transmission of vibrations set up in the working parts to the blower casing is prevented.

I claim:

1. In an oil burner, the combination with a casing providing a blower chamber and a discharge conduit extending from one side of said chamber, said casing having an opening in each of two adjoining sides of the chamber and respectively at opposite sides of said conduit, a resilient element seated in each of said openings, and a member supported in said resilient elements and constituting a common support for a motor, a pump and a blower operatively connected in line extending transversely to the axis of the discharge conduit, said blower being located within said chamber.

2. In an oil burner, the combination with a casing providing a blower chamber and a discharge conduit extending from one side of said chamber, said casing having a circular opening in each of two adjoining sides of the chamber and respectively at opposite sides of said conduit, a resilient ring seated in each of said openings, and a member having annular parts seated respectively in said rings and constituting a common support for a motor, a pump and a blower operatively connected in line extending transversely to the axis of the discharge conduit, said blower occupying a position within said chamber.

3. In an oil burner, the combination with a casing providing a blower chamber and a discharge conduit extending from one side of said chamber, said casing having an opening in each of two adjoining sides of the chamber and respectively at opposite sides of said conduit, a resilient member seated in each of said openings, a structure seating against said resilient elements and being supported through said elements upon the casing, a motor attached to one end of said structure and closing one of said chamber openings, said motor having a shaft extending into said chamber transversely to the axis of said conduit, a pump mounted in the other end of said structure and operatively connected with said shaft, and a blower mounted on the shaft within the chamber.

4. In an oil burner, the combination with a casing providing a blower chamber and a discharge conduit extending from one side of said chamber, said casing having an opening in each of two adjoining sides of the chamber and respectively at opposite sides of said conduit, a resilient element seated in each of said openings, a structure seated on said resilient elements and supported through said elements upon the

casing, a motor attached to one end of said structure and closing one of said chamber openings, said motor having a shaft extending into said blower chamber transversely to the axis of said conduit, a hollow extension at the opposite end 5 of said structure embracing the other of said casing openings and having ports for flow of air through the last-named opening to the blower chamber, a pump mounted on said extension and projecting into the interior of the latter, means 10 for operatively connecting the pump with said shaft, and a blower mounted on said shaft within the said casing chamber.

5. In an oil burner, the combination with a casing providing a blower chamber and a discharge 15 conduit extending from one side of said chamber, said casing having a circular opening in each of two adjoining sides of said chamber and at opposite sides of said conduit respectively, a resilient ring seated in each of said openings, a structure 20 having annular portions seating respectively upon said resilient rings and being supported through said rings upon the casing, one of the annular portions of said structure being extended outwardly from said chamber to form a pump housing 25 and having therein ports for passage of air to the blower chamber, a pump mounted in said extension, a motor mounted at the opposite end of said structure and having a shaft extending into the blower chamber, means for operatively connecting said shaft to the pump, and a blower mounted on said shaft within the blower chamber.

6. In an oil burner, the combination with a casing providing a blower chamber and a discharge conduit extending from one side of said chamber, 35 said casing having an opening in each of two adjoining sides of said chamber and at opposite sides of said conduit respectively and being divided along lines intersecting said openings, an annular rubber element seated in each of said 40 openings and an annular structure seated in said elements and being supported through said elements upon the casing, a motor mounted at one end of said structure and having a shaft projecting into said blower chamber transversely to the 45 axis of said conduit, a pump mounted at the other end of said structure outwardly of said chamber, means operatively connecting the pump with the shaft, and a blower mounted on said shaft within the blower chamber.

7. In an oil burner, the combination with a casing providing a blower chamber and a discharge conduit extending from one side of said chamber, said casing having a circular opening in each of two adjoining sides of said chamber and at opposite sides of said conduit respectively, a rubber ring seated in each of said openings, a structure having annular portions seating respectively in said rings, a motor mounted at one end of said structure and having a shaft extending into the blower chamber transversely to the axis of said conduit, a pump mounted at the other end of said structure outwardly of said chamber, means operatively connecting the pump with said shaft, a blower mounted on said shaft within the 65 blower chamber, and means for positively interlocking the said rubber rings both with the casing and with said structure.

8. In an oil burner, the combination with a casing providing a blower chamber and a discharge conduit extending from one side of said chamber, said casing having an opening in each of two adjoining sides of said chamber and at opposite sides of said conduit respectively, a resilient element seating in each of said openings, 70

5 a structure seating on said resilient elements and supported through said elements upon the casing, a motor attached to one end of said structure and having a shaft projecting into the blower chamber transversely to the axis of said conduit, a cylindrical extension at the other end of said structure outwardly of said chamber, a pump mounted in said extension and operatively connected with said motor shaft, said extension having 10 in the cylindrical wall thereof ports for admission of air to the blower chamber, an apertured sleeve adjustably mounted on said cylindrical extension and affording means for regulating the effective area of said ports, and a blower 15 mounted on said shaft within the blower chamber.

9. In an oil burner, the combination with a casing providing a blower chamber and a discharge conduit extending from one side of said chamber, said casing having an opening in each of two adjoining sides of said chamber at opposite 5 sides of said conduit respectively, a resilient element seated in each of said openings, and a unit assembly supported in said resilient elements and comprising a motor, a pump and a blower operatively connected in line extending transversely 10 to the axis of said conduit, said blower being positioned within the blower chamber, and said motor and pump being positioned outwardly of and at opposite sides of said chamber.

JOSIAH HOWARD VAN SCIVER. 15
